ASSIGNORS TO NEW WAY MACHINE COMPANY, OF JEFFERSON, IOWA, A CORPOR-
ATION OF IOWA.

MEANS FOR REPAIRING RADIATORS AND THE LIKE.

1,353,009.

Specification of Letters Patent. Patented Sept. 14, 1920.

Application filed September 5, 1919. Serial No. 321,899.

To all whom it may concern:

Be it known that we, WILSON M. WRIGHT, CLARENCE TEEPLES, and JAMES J. LAMB, citizens of the United States of America, and residents of Jefferson, Greene county, Iowa, have invented a new and useful Means for Repairing Radiators and the like, of which the following is a specification.

The object of this invention is to provide improved means for repairing, by the use of acid and a soldering substance, reticulated articles such as radiators of motor vehicles.

A further object of this invention is to provide improved means for supporting a reticulated object in and during the operation of applying heat, acid and soldering substance thereto.

A further object of this invention is to facilitate, expedite and lessen the expense of the operation of applying acid to and sealing and soldering rents in reticulated objects such as motor radiators.

A further object of this invention is to provide improved means for receiving and conserving acid.

A further object of this invention is to provide improved means for receiving and conserving soldering material.

A further object of this invention is to provide improved means for mounting and manipulating a heating device in connection with other elements of means for repairing motor radiators.

A further object of this invention is to increase the mobility and convenience in use of the various elements of an equipment for applying acid, heat and solder to parts of motor radiators.

Our invention consists in the construction, arrangement and combination of elements hereinafter set forth, pointed out in our claims and illustrated by the accompanying drawing, in which—

Figure 1 is a plan of the devices embodying our invention. Figs. 2 and 3 are side and end elevations of the same. Fig. 4 is a plan of a solder-holder or pot employed. Fig. 5 is a cross-section on 5—5 of Fig. 4.

In the construction of the means as shown the numerals 10, 11 designate end plates and 12 designates one of a pair of side plates, which plates preferably are made of metal by casting and are assembled and rigidly

connected to form a housing rectangular in plan view, slightly tapering from bottom to top and open at its top and bottom. The housing preferably is supported at desired elevation by legs 13 secured to corners thereof, which legs preferably are made of angle-iron bars. A funnel or gathering device 14 is mounted loosely in the open upper end of the housing and the smaller open end of said funnel occupies a horizontal plane adjacent to the center of the housing. Openings 15 are formed in the end plates 10, 11 and a soldering pot 16 extends horizontally through said openings and is supported by the lower margins thereof. The soldering pot 16 preferably is formed with a transverse partition 17, dividing said pot into two compartments 18, 19 and communication is afforded between said compartments by spacing the partition slightly from the bottom of the pot. Slide-ways 20, 21 are formed on the upper ends of the end plates 10, 11 and project above the side plates 12 and a tray is mounted horizontally for manual reciprocation in said slide-ways. The tray preferably is made of metal by molding and, at one end, is formed as a shallow pan 22 having a spout 23 at the center of its outer wall and, at its other end, said tray is formed as a frame 24 integral with and forming an extension of the pan, which frame is substantially the same depth as the pan and its side bars are adapted to slide in the ways 20, 21. Stops 25 are formed on the outermost corners of the frame 24 and are adapted to engage adjacent ends of the slide-ways and limit movement of the tray therein in one direction. The tray is adapted to be moved across the housing so that the pan 22 will, at times, substantially cover and close the upper end of the funnel 14. A grid 26, preferably made of metal by casting, is superposed relative to the housing and is formed with downwardly extending ears 27, 28 connected by pivots 29 to the slide-ways 20, 21. A brace 30 is fixed at one end to and offset from the end wall 11 and overlaps one side of the grid 26. A series of holes 31 is formed in the brace 30 and registers at times with a hole in the adjacent side of the grid 26 and said holes are adapted to receive a pin 32 to connect the brace and grid detachably. Brackets 33, 34 are suitably mounted on the housing and one leg

respectively and the outer ends of said brackets are in vertical opposition and are formed with registering holes. A tank 35 is mounted between the horizontal arms of the brackets 33, 34 and is provided with alining pins 36, 37 on its ends, which pins are journaled in the holes in said brackets, thus providing means for oscillation of the tank on a vertical axis. A valve-controlled feed pipe 38 communicates at one end with and extends laterally from the lower portion of the tank 35 and a burner 39 is mounted on the outer end portion of said pipe. The pipe 38 and burner 39 are located in a horizontal plane beneath the housing and they, together with the tank, may be oscillated to carry the burner through an arc relative to the vertical center of the housing.

In practical use, a radiator to be repaired is first cleaned adjacent to a break or rent therein by scraping. Then the radiator is placed on the grid 26 in substantially horizontal position, the pot is removed, fire is generated at the burner 39, preferably fed by gasoline from the tank 35 through the pipe 38, the burner is moved through an arc to a position beneath the open lower end of the funnel 14, the tray is adjusted laterally to register the opening in the frame thereof with the funnel, and the radiator is adjusted laterally to register the broken portion thereof with said funnel. Heat rising from the burner through the funnel raises the temperature of the broken part of the radiator to the desired degree. Then the tray is adjusted laterally to locate the pan 22 over the funnel, the pot supplied with solder, preferably of low grade, is positioned in the holes 15 and receives direct and immediate action of the heat rising from the burner to the end of melting the solder therein. Then acid in liquid form is poured over the pre-heated broken part of the radiator, engages with and thoroughly cleanses said part and the drippings of the acid are received in the pan 22 and recovered therefrom through the spout 23 for repeated use. Then, the solder being melted, the grid and radiator thereon are oscillated manually and adjusted by means of the brace 30 and pin 32, the tray is adjusted laterally to move the pan 22 away from the funnel, and molten solder is lifted, preferably by means of a ladle not shown, from the projecting compartment 18 and poured over the broken part of the radiator. The molten solder contacts with and flows over the cleaned, acid-treated broken part of the radiator and through the spaces of said radiator, and drippings of said solder drop and flow through the funnel 14 and are gathered thereby into the compartment 19 of the pot. Desired temperature of the radiator, funnel and pot are maintained by heat rising from the burner 39, hence only the small quantity of solder

necessary to seal the rent is retained in and on the radiator, the remainder flowing off and being recovered in the compartment 19 of the pot. The clean usable solder settles to the bottom of the compartment and flows through the space beneath the partition 17 to be dipped from the compartment 18 in succeeding operations, while the slag and waste is retained in the compartment 19. The grid and radiator thereon may be oscillated to any desired degree as may be indicated to present any broken surface of the radiator to the poured molten solder. The heat is regulated by the position of the burner, or the location of the pot and tray, or by adjusting the supply of fuel by means of the valves of the pipe 38.

We claim as our invention:

1. Means for repairing radiators and the like, comprising a suitable support, a carrier for a work object articulating on said support, adjusting means connecting said carrier and support, and a tray mounted for transverse reciprocation between said support and carrier, which tray includes a pan and an open frame adapted to register selectively with said support.

2. Means for repairing radiators and the like, comprising a tubular support arranged with its opening upright, a carrier for a work object superposed on said support, a tray located beneath said carrier and adapted for reciprocation transversely of said support, which tray includes a pan and an open frame, a pot within said support beneath the tray, a fuel tank and a burner connected with said tank and adapted for location beneath said pot.

3. Means for repairing radiators and the like, comprising a tubular support arranged with its opening upright, a carrier for a work object superposed and articulating on said support, adjusting means connecting said carrier and support, a tray located beneath said carrier and adapted for reciprocation transversely of said support and across the opening therein, which tray includes a pan and an open frame, a pot within the bore of said support, a fuel tank and a burner connected with said tank and adapted for location in registry with said bore beneath said pot.

4. Means for repairing radiators and the like, comprising a tubular support arranged with its bore upright, a carrier for a work object superposed and articulating on said support, means for adjusting oscillation of said carrier on said support, a tray located beneath said carrier and adapted for reciprocation transversely of said bore, a pot within the bore of said support, a fuel tank mounted for oscillation on said support, a pipe leading from said tank and a burner on said pipe adapted to be moved through an arc relative to said bore.

5. Means for repairing radiators and the like, comprising a tubular support arranged with its bore upright, a carrier for a work object superposed and articulating on said support, means for adjusting oscillation of said carrier on said support, a pot within the bore of said support, a fuel tank mounted for oscillation on said support, and a burner carried by and supplied from said tank, which burner is movable through an arc, coincident with oscillation of said tank, to and from a position registering with said bore beneath said pot.

6. In means for repairing radiators and the like, a tubular support having its bore upright and formed with opposed slideways on its upper end, a grid superposed relative to said support, extending across and articulating on said slideways, a tray mounted for reciprocation in said slide-ways, and heating means registering with said bore beneath said tray.

7. Means for repairing radiators and the like, comprising a tubular support arranged with its bore upright, a carrier for a work object superposed and articulating on said support, a funnel mounted in the bore of said support, a pot mounted in the bore of said support beneath said funnel and heating means registering with said bore beneath said pot.

8. Means for repairing radiators and the like, comprising a tubular support arranged with its bore upright, a carrier for a work object superposed and articulating on said support, a funnel mounted in the bore of said support, a pot mounted in the bore of the support beneath said funnel, a tank mounted for oscillation on said support, and a burner carried by said tank and adapted

to be moved through an arc by oscillation of the tank, to and from a location registering with said bore and beneath said pot.

9. In means for repairing radiators and the like, a support, a pot therein, a carrier superposed on the support, and a tray interposed between the carrier and pot, said tray having a pan adapted to intercept passage from said carrier to said pot and also having an open frame adapted to permit passage from said carrier to said pot.

10. In means for repairing radiators and the like, a support formed of side and end plates suitably connected and legs therefor, said end plates being formed with slideways, a grid articulating on said slide-ways, a funnel depending within said support, a tray mounted for reciprocation in said slide-ways above said funnel, said end plates being formed with openings, a pot mounted in said openings and extending across said support beneath said funnel, and heating means communicating with the interior of the support beneath said pot.

11. In means for repairing radiators and the like, a support formed of side and end plates suitably connected and legs therefor, said end plates being formed with openings, a grid superposed and articulating on said end plates, a funnel depending within said support, a pot in said openings and extending across and beneath the funnel, and heating means adapted to register with the interior of the support and beneath said pot.

Signed at Jefferson, in the county of Greene and State of Iowa, this 27th day of August, 1919.

WILSON M. WRIGHT.
CLARENCE TEEPLES.
JAMES J. LAMB.
